UNITED STATES PATENT OFFICE.

JOSEPH WIESER, OF NEW YORK, N. Y.

AUTOMATIC GOVERNOR FOR PNEUMATIC MOTORS.

No. 806,609.

Specification of Letters Patent.

Patented Dec. 5, 1905.

Application filed March 2, 1905. Serial No. 248,128.

To all whom it may concern:

Be it known that I, JOSEPH WIESER, a citizen of the United States, residing in New York, borough of Brooklyn, in the State of New York, have invented certain new and useful Improvements in Automatic Governors for Pneumatic Motors, of which the following is a specification.

This invention relates to an improved automatic governor for pneumatic motors which are employed in mechanical musical instruments, such as self-playing pianos and the like, for operating the devices by which the perforated music-sheet is actuated, the governor being designed with a view of insuring the uniform action of the motor regardless of the variations of pressure in the motor-bellows or the speed or force of the pedal-action for operating the pump-bellows, the object of the governor being to produce an approximately uniform pressure in the wind-chambers and pneumatics of the motor, and thereby the even motion of the music-sheet.

With these ends in view the invention consists in the novel features of construction and combinations of parts, which will be fully described hereinafter and finally pointed out in the claims.

In the accompanying drawings, Figure 1 is a front elevation of my improved automatic governor for pneumatic motors shown in position for use in a self-playing piano. Fig. 2 is a side elevation of the same, showing its connection with the pedal-operated pump-bellows. Fig. 3 is a vertical transverse section on line 3-3, Fig. 1, showing the pump-bellows, motor-bellows, and the parts composing the automatic governor in a position of rest. Fig. 4 is a similar vertical transverse section showing the parts in a collapsed position for regulating the suction action on the pneumatic motor. Fig. 5 is a side elevation of the motor-bellows, taken from the opposite side and showing the adjusting-lever mechanism for the valve actuated by the movable member of the motor-bellows; and Fig. 6 is a sectional front elevation of the parts shown in Fig. 1, showing the interior parts of the same, some of them being broken away.

Similar letters of reference indicate corresponding parts throughout the several views.

Referring to the drawings, B designates the motor-bellows, and B' the suction-bellows for

the pneumatic valve-actions V, of which there is one more than is necessary to operate the pneumatics by which the key-actuating lifters (not shown) of a piano or other musical instrument are operated under the influence of a perforated traveling music-sheet. The purpose of the extra valve-action will be described hereinafter. The motor-bellows B and suction-bellows B' are operated by the pump-bellows P and the latter by a suitable lever connection with the pedal P'. The motor-bellows B is connected by an opening b and channel b' in its stationary wall or member and a flexible tube b'' with the wind-chest of the motor, while the suction-bellows B' is connected with the wind-chest of the valve-actions V. The pneumatic motor which drives the music-sheet is not shown in the drawings; but it is located at any suitable point of the self-playing piano or other mechanical musical instrument in proximity to the music-sheet driving mechanism.

The motor-bellows B is provided between its stationary and movable members with a V-shaped spring S, the tension of which expands the bellows in opposition to the suction action of the pump-bellows, which latter exerts a collapsing action on the motor-bellows. The motor-bellows B is further provided at its inside on its stationary member with a sliding cut-off valve D, which is guided in upright ways d and which is provided with an opening or openings o, adapted to be shifted into and out of register with an opening o' in the stationary member, said opening o' communicating with the wind-channel o'', leading to the pump-bellows P. The cut-off valve D is connected by a pivot-rod d', which is guided in an opening in the lower part of the motor-bellows B, with a governor-pneumatic G, supported below the same, said pneumatic being connected by a flexible tube g with the valve-chamber of the extra pneumatic valve-action V, before mentioned, said action being preferably arranged at the end of the tier of valve-actions, as shown in Fig. 1. To the side of the movable member of the motor-bellows B, adjacent the suction-bellows B', is applied a pivoted lever f, which carries at its lower end a valve f', serving to open or close a stationary duct f'', which is connected by a flexible tube f''' with the dia-phragm-chamber of the extra valve-action V,

as shown clearly in Figs. 3 and 4, said lever being capable of adjustment by means of a set-screw f^4 , located in a lug f^5 , attached to the movable member of the regulator-bellows, 5 so as to permit thereby the adjustment of the valve f' to a greater or smaller distance from the port of the stationary duct f^2 , which is opened or closed by the valve f' by the vibrations of the movable member of the 10 motor-bellows as the same is alternately expanded under the tension of its spring or collapsed under the influence of the suction action of the pump-bellows. The pivoted valve-carrying lever f is acted upon by a spring f^6 , 15 which is shown in Fig. 5, and which holds it against the set-screw f^4 , so as to cause the lever f to follow the motions of the movable member of the motor-bellows and press the valve f' either tightly against the port of the duct f^2 for closing the same or move it away 20 from the port for opening the duct f^2 .

The wind-chest of the valve-actions V is connected by an air-channel with the suction-bellows B', as indicated in Figs. 1 and 6, so that 25 the space immediately above the diaphragm of the valve of the extra valve-action is always under the influence of suction. As a consequence as soon as the valve f' of the motor-bellows B opens the stationary duct f^2 30 the atmospheric air, which enters the tube f^3 , destroys the equilibrium of the valve-diaphragm, which is then raised by suction and carries with it the valve, so that suction is created in the valve-chamber and by means 35 of the tube g in the governor-pneumatic G. This pneumatic in collapsing moves the cut-off valve D upwardly, whereby the openings in said valve register with the openings o' and permit thereby the pump-bellows to exert 40 a greater suction action on the motor-bellows and produce the collapsing of the same. The vibration of the movable member of the motor-bellows against the tension of its spring under the influence of the suction action of 45 the pump-bellows when the openings $o o'$ register with each other produces the closing of the valve f' on the port of the stationary duct f , by which the inlet of air to the diaphragm-chamber of the valve-action V is interrupted and the pneumatic valve and its diaphragm returned by gravity into their former or normal position, so that the governor-pneumatic G is instantly expanded by its spring when the atmospheric pressure which passes 55 through the top of the valve-chamber and through the connecting-tube g is admitted into the same. The cut-off valve D is thereby moved in downward direction by the spring of the governor-pneumatic G, so that the suction action of the pump-bellows on the motor-bellows is momentarily interrupted and the movable member of the same returned under the action of its spring S into outward or

expanded position, as shown in Fig. 3. By the expansion of the motor-bellows B the valve 65 f' is moved away from the port of the stationary duct f^2 and the latter opened, so that the diaphragm and valve of the valve-action V are again actuated, the governor-pneumatic G collapsed, and the cut-off valve returned into 70 raised position, restoring thereby the connection of the motor-bellows with the pump-bellows and producing the collapsing of the motor-bellows, the alternating expansion of the 75 motor-bellows under the influence of its spring and collapse by the suction action of the pump-bellows by the actuation of the pneumatic valve-action V and the governor-pneumatic G producing the alternating up-and-down movement or play of the cut-off valve D, so that a 80 uniform suction pressure is established in the motor-bellows and by the same on the pneumatic motor, so that the regular motion of the music-sheet is obtained.

As all the air which enters and operates the 85 pneumatic motor passes through the motor-bellows and as the motor-bellows is alternately expanded by its spring and collapsed under the suction action of the pump-bellows, in connection with the action of the vibrating 90 valve f' on the stationary duct f , and the action of the pneumatic valve-action on the governor-pneumatic and the sliding cut-off valve, the motor-bellows is fully and sensitively responsive to the variations of air-pressure on 95 the same. Consequently when the exhaust force of the pump-bellows becomes excessive by rapid pumping the motor-bellows becomes partially collapsed and produces by the closing 100 of its valve on the stationary duct the expansion of the governor-pneumatic and thereby the lowering of the cut-off valve, and consequently a reduction of the exhaust force of the pump-bellows, so that the motor-bellows is permitted to expand under the tension of its spring, 105 produce the actuation of the pneumatic valve-action, collapse of the governor-pneumatic, and lifting of the cut-off valve, and so the quick and effective play of the parts and the regulation of the motor-bellows and pneumatic motor actuated thereby. When the action 110 of the pump-bellows is diminished from any cause, the motor-bellows is expanded under the action of its spring, its valve is moved away from the stationary duct, so that the corresponding actuation of the cut-off valve takes place, whereby the passage of air from the motor-bellows to the pump-bellows is facilitated and an increased suction on the pneumatic motor exerted.

The motor-bellows and the automatic valve-action by which the governor-pneumatic of the cut-off valve is operated are very effective for regulating the suction action of the air on the pneumatic motor, so that a uniform 125 motion is imparted thereto. The pneumatic

motor is thereby made independent of variations in the pressure of the pump-bellows or of the speed or force of the pedal action, and is thereby enabled to drive the music-sheet at 5 a uniform speed.

Having thus described my invention, I claim as new and desire to secure by Letters Patent—

1. In a governor for pneumatic motors, the combination, with the motor-bellows, of a 10 valve for regulating the suction exerted on the same, a pneumatic for operating said valve, and means governed by the amount of inflation of said motor-bellows for collapsing and expanding said pneumatic.

15 2. In a governor for pneumatic motors, the combination, with the motor-bellows, the pump-bellows, and the passage connecting the same, of a valve slideable on the fixed part of said motor-bellows and operable to control 20 said passage, and means governed by the inflation of said motor-bellows for actuating said valve.

25 3. In a governor for pneumatic motors, in combination, with the motor-bellows, and the passage for suction air communicating with the fixed part of the same, an interior valve in said motor-bellows slideable upon the fixed part of the same and provided with an opening adapted to be shifted into or out of register with said passage, and means for actuating said valve.

30 4. In a governor for pneumatic motors; a motor-bellows, a suction air-passage leading thereto, a valve in said motor-bellows for controlling said passage, a pneumatic, and an operative connection between said pneumatic and said valve.

35 5. A governor such as described, including a motor-bellows, a suction air-passage leading 40 to the fixed wall of the same, an interior valve slideable on the rear wall or fixed part of said motor-bellows and operable to control said passage, a pneumatic governed by the inflation of said motor-bellows, and a rod connecting the movable part of said pneumatic with 45 said interior valve.

6. In a governor such as described, the combination with the motor-bellows, and the pneumatic for controlling the suction in the same, 50 of a valve-action in communication with said pneumatic, and means governed by the inflation of said motor-bellows for controlling such communication.

7. In a governor for pneumatic motors, a 55 motor-bellows, a suction air-passage leading thereto, a valve for controlling said passage, a pneumatic for actuating said valve, a valve-action in communication with said pneumatic, and a valve carried by the movable member 60 of said motor-bellows for controlling such communication.

8. In a governor for pneumatic motors, the combination, with the motor-bellows, and the

pneumatic for controlling the suction therein, of a valve-action, a passage leading from the 65 valve-chamber of said valve-action to said pneumatic, and means controlled by the inflation of said motor-bellows for actuating the valve of said valve-action and thus producing a suction in said passage.

70 9. In a governor for pneumatic motors, a motor-bellows, a pneumatic for controlling the suction therein, a valve-action, a passage leading from the valve-chamber of the latter to said pneumatic, a passage leading to the diaphragm-chamber of said valve-action, and a valve carried by the movable member of said motor-bellows for controlling said last-named passage.

75 10. The combination, with a spring-expanded motor-bellows, of a governor-pneumatic, a sliding cut-off valve located in the wind-channel between said motor-bellows and the pump-bellows, a pneumatic valve-action, a stationary duct, connecting-ducts between the valve-action and the governor-pneumatic and the stationary duct, and a regulable valve on the movable member of the motor-bellows arranged to open or close said stationary duct for regulating the internal pressure of the 90 motor-bellows.

80 11. The combination, with a spring-expanded motor-bellows and its connection with the motor-engine, of a motor-regulator, consisting of a cut-off valve located in the channel leading to the pump-bellows from said motor-bellows, a governor-pneumatic connected with said cut-off valve, a pneumatic valve-action connected with said governor-pneumatic, a stationary duct also connected with said valve-action, and a valve supported on the movable part of the motor-bellows and adapted to open or close said duct so as to actuate the governor-pneumatic and produce the collapse or inflation of said motor-bellows.

85 100 105 110 115 120 125 12. The combination, with a spring-expanded motor-bellows and pump-bellows, of a duct leading from the motor-bellows to the pneumatic motor, a governor-pneumatic, a cut-off valve actuated by said pneumatic and located in the wind-channel between the motor-bellows and pump-bellows, a pneumatic valve-action connected with the governor-pneumatic for actuating the same, a stationary duct connected with the diaphragm-chamber of the valve-action, a valve on the movable member of the motor-bellows adapted to open or close said duct by the vibrations of said member, so as to actuate the governor-pneumatic and regulate the suction action of the motor-bellows.

13. The combination, with a spring-expanded motor-bellows and its connection with the pneumatic motor for the music-sheet, of a sliding cut-off valve controlling the wind-channel between the motor-bellows and pump-bellows,

a governor-pneumatic connected with said cut-off valve, a pneumatic valve-action, a flexible tube connecting the valve-chamber of said valve-action with said governor-pneumatic, a stationary duct, a pipe connection between said duct and the diaphragm-chamber of the valve-action, a valve on the movable member of the motor-bellows adapted to open or close the stationary duct by the vibrations of said

movable member, and means for adjusting said valve relatively to said duct.

In testimony that I claim the foregoing as my invention I have signed my name in presence of two subscribing witnesses.

JOSEPH WIESER.
